DOUBLE ACTING, TWO-CYCLE DIESEL
ENGINE

Walter R. Appeman, Champaign, Ill.

Application November 29, 1943, Serial No. 512,170

17 Claims. (Cl. 123—54)

This invention relates to internal combustion engines of the two-stroke cycle Diesel type, and the improvements herein described undertake to embody in such Diesel engine certain structural features and principles of operation as are disclosed in my patent numbered 2,335,252, dated November 30, 1943.

The main object of the invention is to provide a double action, two-stroke cycle Diesel type engine, consisting of one or more engine units, each unit comprising a pair of elongate cylinders closed at their ends and mounted together in parallel spaced relation and exact transverse alignment, pistons reciprocably mounted in the ends of each cylinder and in exact transverse alignment as between the two cylinders of each engine unit, the two pistons of each cylinder being rigidly joined together by piston rods or bars, means for rigidly connecting the two piston rods of each engine unit transversely, so that all four pistons of the unit may reciprocate together, means for operatively connecting the said unitary piston assembly to the crank pin of a crank shaft, and means on the cylinders and the engine unit cooperating with the pistons therein, for simultaneously reproducing in the transversely aligned ends of the cylinders of the unit, the conventional phases of two-stroke-cycle Diesel engine operation, whereby a power impulse may be imparted to the crank shaft upon each half turn thereof of one hundred and eighty degrees.

Another object of the invention is to provide in an engine of the type above referred to, in unitary form, a pair of elongate engine cylinders, closed at their ends and arranged in parallel and spaced relation, the cylinders having openings formed medially through their inner adjacent sides in the axial plane of the cylinders, pairs of pistons rigidly mounted on the ends of piston rods or bars and reciprocably seated in the ends of the cylinders in exact transverse alignment, a piston and piston rod carrier, yoke or linkage extended transversely through the said cylinder openings and rigidly anchored at its ends to the said piston rods to form a unitary piston and rod assembly or unit rigidly connected in all its parts, the said carrier, yoke or linkage thus subtending the space between the pair of cylinders, a drive or thrust arm extended forwardly from the forward side of the said cross-yoke between the cylinders, in the axial plane thereof and in parallel alignment with the piston rods therein, there being a connecting rod fork or yoke at the forward end of the said drive arm adapted for receiving the inner end of a connecting rod, a race-way casing

mounted between the forward ends of the cylinders and into the rear open end of which the said drive arm is extended, there being pairs of spaced and parallel track-ways formed or mounted on the opposite inner faces of the sides of the casing disposed adjacent the two cylinders, the surfaces of the track-ways of each pair, on either side of the race-way being slightly off-set from each other, and extended at each side in parallel planes 5 slightly spaced apart, the said planes cutting perpendicularly the common plane of the cylinder axes, a connecting rod operatively journaled at its inner end upon a wrist pin passed through the yoke of the drive arm and at its forward end 10 upon the crank pin of a drive shaft, the ends of the wrist pin of the yoke being extended outwardly thereof, pairs of conventional roller-ring units rotatably seated upon the extended ends of the wrist pin, the said roller-ring units being located at each side upon the said track-ways in 15 such manner that upon the reciprocation of the drive arm in one direction, one set of the rings will rotate in one direction and the other set in the opposite direction, and will rotate reversely 20 as the drive arm moves in the opposite direction, whereby the connecting rod yoke of the drive arm is reciprocably supported upon the two pairs of roller-ring units for receiving and carrying the angular thrusts of the connecting rod from either 25 side of the crank-shaft, two of the roller-rings, one at each side of the race-way having traction only on the track-ways or rails lying in one plane, and the other two roller-rings one at each side 30 having traction only on the track-ways or rails lying in the other or off-set plane, the cylinders being formed and equipped at each end thereof co-operatively with the pistons therein for simultaneously reproducing in the transversely aligned 35 ends of the pair of cylinders, the conventional phases of two-stroke cycle Diesel engine operation, whereby a power impulse is imparted to the crank-shaft of the engine upon each half-turn thereof, or on each reciprocation of the piston and rod assembly or unit.

40 Still another object of the invention is to provide in an internal combustion engine, a unitary, multiple cylinder and piston assembly, comprising a pair of elongate, two-part cylinders, the parts of each cylinder being bolted together endwise at their inner, open, axially aligned and abutted ends, the outer ends of the cylinder parts being closed and being formed and equipped with air intake ports and valves, spent gas exhaust ports, and fuel injectors, in accordance with conventional two-cycle Diesel engine practice, the

45

assembly of cylinders being supported in parallel spaced relation and exact transverse alignment and provided with a unitary piston assembly or unit comprising transversely aligned pistons reciprocably mounted in the four ends of the cylinders and rigidly connected by piston rods, and the piston rods in turn being rigidly connected transversely by means of a yoke or linkage passed through openings formed longitudinally through the inturned adjacent sides of the cylinders, and means for so controlling and timing the admission of air and fuel oil into the combustion chambers of the cylinders with relation to the movement of the pistons therein for opening and closing the cylinder exhaust ports, as to simultaneously reproduce, alternately in the transversely aligned cylinder ends, the several operative phases of operation of a two cycle Diesel engine, and a connecting rod operatively connecting the said piston linkage with the crank of a crank-shaft, for completing the engine assembly, and whereby a two-fold power impulse may be imparted to the crank-shaft upon each oscillation of the said piston assembly or unit.

Still another object of this invention is to provide an engine assembly of the kind referred to, comprising frontal and rear engine casings horizontally aligned and secured together at their open inner ends, a battery of engine units mounted within the casings, each unit comprising a set of four cylinder receptacles formed or mounted in pairs within the outer ends of the casings and positioned horizontally one over the other at each end, the said receptacles being thus arranged in both longitudinal and vertical spaced alignment and relation as to each unit of four receptacles, there being medial openings between or at the inner ends of the vertically spaced receptacles of each unit at each end of the unit, steel cylinder shells locked within the receptacles, casings for air-inlet ports and their spring-set valves at the ends of the assembly and there being fuel injector nozzles extended through said casings, crank-shaft casings secured to the frontal engine casing, a crank-shaft journaled transversely through the crank-shaft casing forwardly of the cylinders at that end, the crank-shaft being extended transversely of the cylinder ends in a plane passed medially and horizontally between the cylinders and perpendicularly to the axial planes of the cylinder units, said crank shaft being formed with cranks and crank-pins aligned in the axial planes of the cylinder units, pistons reciprocably mounted within the four cylinder shells of each engine unit of the battery and arranged in exact vertical alignment at each end of each unit, piston rods rigidly connecting the pistons within each longitudinally spaced pair of pistons of each unit, yokes rigidly and vertically connecting the two piston rods of each unit through the said medial openings at the inner ends of the cylinder receptacles, connecting rods operatively connecting at their ends the several cross-yokes of the engine units with the several aligned crank-pins of the cranks of the crank-shaft, upper and lower cam-shafts journaled and supported horizontally across the front and rear ends of the assembly, in parallelism with the crank-shaft and in the common axial planes of the upper and lower series of cylinders comprising the battery, cams on the cam-shafts for operating the spring-set valves of the air inlet ports, a master gear on the crank-shaft outwardly of one side of the engine casings, gears on the ends of the cam-shafts at the same side of the casings and aligned with

the master gear of the crank-shaft, intermediate gears supported on stub-shafts extended from the side of the casings and operatively intermeshing with each other and with the said master gear and cam-shaft gears, the said master gear of the crank-shaft and the cam-shaft gears being of equal diameter, whereby the cam-shafts and attached cams are rotated at engine speed, for operating the air-inlet valves alternately at each end in unison, and cams on the cam-shafts for operating conventional cam-operated means for injecting fuel oil through the said injector nozzles at each end alternately and in unison at the proper point of air-compression within the cylinder ends of each engine unit, there being exhaust ports leading from the inner ends of the cylinders of each engine unit, operatively spaced from the pistons.

With the foregoing objects in view, together with such other and additional objects and advantages as may be developed in the following specification, attention is directed to the accompanying drawings as embodying certain preferred structural features of the invention, and wherein:

Figure 1 is a plan view of a three-unit engine assembly or battery, showing the three units mounted together side by side within the engine casings and arranged for operating a common crank-shaft.

Figure 2 is a side elevational view of the assembly of Figure 1, certain interior working and stationary parts of the assembly being indicated in dotted lines.

Figure 3 is a top plan view on an enlarged scale of an individual engine unit, as located at the left hand side of the assembly as shown in Figure 1 (the other two units being broken away), including the master gear of the crank-shaft, the cam-shaft gears and intermediate connecting gear train, for operating the air-inlet valves and fuel oil injectors at the two ends of the assembly.

Figure 4 is a longitudinal section on an enlarged scale, on the line 4-4 of Figure 1, looking in the direction indicated by the arrow.

Figure 5 is a transverse section on an enlarged scale, on the line 5-5 of Figure 1, looking forwardly as indicated by the arrow, showing the cylindrical receptacles for the cylinder shells, with the channels provided for the liquid cooling systems, and the race-ways or guide-ways for supporting the ring-roller bearings of the connecting rod yokes, the upper and lower and right hand side portions of the assembly being broken away.

Figures 6 and 7 are detail views, partly in section, showing the method provided for locking together the several pistons and piston rods or bars of each engine unit.

Figure 8 is a longitudinal vertical section along and through one side of the special form of guide-way or race-way as here provided for supporting the connecting rod yoke, showing the ring-roller bearings at that side as positioned upon their track-ways.

Figure 9 is a cross section on the line 9-9 of Figure 8.

Figure 10 is a perspective view on a greatly enlarged scale of the cross-yoke, carrier or linkage, for rigidly connecting a pair of pistons of an engine unit, showing the piston rods and also the forwardly extended drive or thrust arm with connecting rod yoke formed integrally therewith at its forward end.

Figure 11 is a cross-section on the line 11-11 of Figure 10.

The drawings show a three-unit, double acting two-stroke cycle Diesel engine assembly, as mounted within a suitable form of casings in operative relation, and wherein is presented a preferred exemplification of the principles of this invention.

As shown in the drawings, this three-unit assembly, here represented generally as units A, B, and C, is disposed horizontally for the purposes of description, and the unit is represented as a whole by the numeral 5. Obviously any desired number of such engine units may be assembled in similar unitary form.

This three-unit assembly 5 is housed or incased in a suitable housing or casing which comprises as here shown, a frontal engine casing 6, a rear engine casing 7, frontal and rear valve and air-port casings 8 and 9, and frontal crank and cam-shaft casings 10 and 11, all aligned and abutted together in operative relation as shown. The engine casings 6 and 7 entirely encompass the three engine units A, B, C, at top, bottom and sides, but not at the ends thereof, the ends being provided for by the end casings 8, 9, 10, 11, in manner later to be pointed out. Interiorly of the casings 6 and 7, preferably formed integrally therewith but in any event supported therefrom, are the vertical and longitudinally extended webs 6a, 7a, equally spaced from the sides of the casings and from each other, so as to divide the interior of the casings into three longitudinally extended compartments for receiving the elements of the three engine units A, B, C. Within the outer ends of each of these compartments, front and rear, are mounted or integrally formed therewith, sets of four cylinder receptacles or chambers, to-wit: receptacles 12, 12a and 13, 13a for the engine unit A; receptacles 14, 14a and 15, 15a for the engine unit B; and receptacles 16, 16a and 17, 17a for the unit C. These cylinder receptacles or chambers of each engine unit, are arranged in pairs and in spaced relation and alignment both longitudinally and vertically, as represented at 12-12a and 13-13a for the longitudinal and axially spaced alignment of the upper and lower receptacles of the unit A, and as represented at 12-13, and 12a-13a for the vertical and spaced alignment of the frontal and rear receptacles of the unit A. Similar disposition and arrangement is made as to the receptacles 14-14a, 15-15a of the unit B, and the receptacles 16-16a, 17-17a of the unit C. The described cylinder receptacles are formed at their outer ends with conventional annular channel-ways 18 for liquid cooling of the units, and outwardly of these channel-ways the cylinder receptacles are notched annularly around their outer ends to provide the annular shoulders as indicated at 19 for a purpose to be described. At the top and bottom of the engine casings 6 and 7, or through the upper and lower sides of the cylinder receptacles of each engine unit, in proper position and alignment relative to the inner ends of the receptacles for the purposes and functions of the engine, exhaust ports 20 are formed, immediately inward of the channel-ways 18, and which exhaust ports lead into the exhaust manifolds 21.

The inner ends of the cylinder receptacles of each engine unit within the rear engine casing 7, are subtended and supported by the webs 7b, and the inner ends of the cylinder receptacles within the forward engine casing 6 are reinforced by the webs 6b, and which are cut away medially to form the drive-arm openings or clearances 6c. Steel cylinders or cylinder shells 25, 25a, all of

equal length and diameter and open at both ends, are firmly seated within all of the cylinder receptacles as described, being pressed thereinto through the outer ends of the receptacles. The outer ends of these cylinders 25, 25a are turned perpendicularly outward to form the annular flanges 25b adapted to snugly seat within the described annular notches and against the shoulders 19 at the outer ends of the receptacles. These cylinders 25, 25a are all formed with exhaust ports 26, which are adapted to register with the exhaust ports 20 of the cylinder receptacles when the cylinders are properly seated therein. And as these cylinders or cylinder shells are thus forced into their receptacles, their inner ends close over the channel-ways 18 of the receptacles, thus completing the said channel-ways.

Within the four cylinder-shells of each of the three engine units A, B, C, there are reciprocably mounted four pistons 27, 27a, the same being formed with relatively short skirts as shown, and with the conventional grooves for receiving piston rings. These pistons are rigidly mounted in longitudinally extended pairs upon the ends of piston rods 28, all of equal length and preferably of I-beam structure in cross-section for the sake of strength and lightness, and are of "cantilever" formation from end to end, as shown in Figure 10. As stated the pistons are all formed with relatively short skirts, and may be provided at their inner sides with the inwardly extended tongues 27b, arcuate in cross-section to conform with the curvature of the cylinder shells, and which tongues are arranged and adapted for slidably and alternately at each end of the engine units, closing the exhaust ports of the unit, for preventing the back-flow of exhaust gasses into the cylinders. The outer faces of the pistons may have welded thereonto, fire plates 27c, of any suitable metal for the purpose and best adapted to resist the high temperatures incident to the operation of such an engine. The pistons 27, 27a, are formed within their skirts with the integral cups or hollow bosses 27d adapted to snugly receive the reduced and rounded extremities 28a of the piston rods 28. The shoulders of the rods immediately back of the extremities 28a are also rounded to the same diameter as the outer diameters of the bosses 27d, and these shoulders are threaded as shown at 28b while the outer sides of the bosses themselves are reversely threaded as shown at 27e. Locking rings or collars 29 are provided, of equal inner diameter with the outer diameter of the threaded shoulders 28b of the piston rods 28. The collars 29 are threaded interiorly and reversely from each side, as indicated at 29a, 29b, to mesh with the threads 27e of the hollow bosses 27d and the threads 28b of the piston rods 28. Then by threading these collars first half-way upon the hollow bosses and then threading the ends of the rods reversely down into the remaining or open portions of the collars, the elements may be firmly locked together. Small holes 29c are pierced through the collars 29, spaced apart to include the threading both of the rods and of the bosses, and double pointed pins 30 are then driven down through these holes with one leg impinging the threads of the bosses and the other leg the threads of the rods, thus locking the elements against unturning.

Cross-yokes or links 31, formed with the open and angularly divergent branches 31a at their ends, are by these slanting and divergently branched ends integrally connected or welded to the pairs of piston rods 28 within each engine

unit, the elements being all equally disposed and transversely aligned at each side, and so that the pistons of each unit, within the transversely aligned ends of the cylinders, are also exactly transversely aligned, and the whole assembly of pistons, rods and cross-yokes of each unit, form a reciprocable, floating unit, working in co-operation with the similar assemblies of the other engine units as embodied in the full engine assembly. The assembling of the pistons, piston rods and cross-yokes may be first done before their insertion in the cylinders, and they may then be inserted in place within the cylinders by drawing the casings 6 and 7 apart for this purpose and then joining and locking them together in manner later to be pointed out. In this assembly the piston rods are of course to be of such length that the pistons are all spaced, relative to the exhaust ports 20—26, so that when the piston unit of any engine unit is reciprocated, and two transversely aligned pistons move fully into one end of the pair of cylinders, the exhaust ports in the opposite cylinder ends will be uncovered for the escape of spent gasses of combustion therethrough, while at the same time the tongues of the leading pistons will close the exhaust ports of their cylinders and keep them closed during the compression movement of these pistons, thereby preventing the back-flow of spent gasses from the manifolds into the cylinders.

The frontal and rear valve and air-port casings 8 and 9 are positioned transversely across the frontal and rear ends of the casings 6 and 7 and over the ends of the several cylinder receptacles and cylinder shells contained therein. These casings are formed with the air-inlet ports 32 and the nozzles of fuel oil injector pipes are passed through these casings, the nozzles being indicated at 33a and the pipes at 33, all opening into the cylinder ends of the engine units and being of conventional form and structure as designed for this type of engine. These casings are also formed with the usual valve openings and valve seats 34 and carry the push-valves 35, the headed stems of which are slidably passed through guide bosses 36 formed on the casings in axial alignment with the cylinders, these valves being held normally closed by the encircling coil springs 37, in conventional manner. Conventional means (not shown) are employed for forcing air under pressure through the air-inlet ports into the cylinders, for injecting and spraying fuel oil under pressure through the nozzles into the cylinder ends, and for properly timing and synchronizing these operations with the movements of the air-inlet valves and the reciprocations of the pistons for causing the engine assembly to function as designed and intended.

Crank and cam-shaft casings 10 and 11 are positioned transversely over the frontal end of the engine assembly as described, and all of the described engine casings, frontal and rear, are then firmly bolted and anchored together by means of tie-rods 38 passed longitudinally through the assembly from end to end, and secured by nuts 38a upon their threaded ends. A crank-shaft 39 is journaled transversely and horizontally through the frontal casings 10 and 11 in bearings 40 carried by these casings and by brackets 41 extended forwardly from the casing 8. This crank-shaft is located forwardly of the engine assembly or unit 5, with its axis in a plane extended exactly mid-way between the pairs of upper and lower cylinders and cutting perpendicularly through the vertical axial planes of the cylinders

of the several engine units A, B, C. The crank-shaft is formed with three cranks 39a, 39b, 39c, which are each centrally aligned with their respective engine units A, B, C, and these cranks are spaced angularly apart around the crank-shaft one hundred and twenty degrees in the axial planes of their respective cylinders.

Upper and lower cam-shafts 42, 43, are journaled horizontally across the frontal and rear ends of the upper and lower series of cylinders of the three units A, B, C, in spaced relation to the said ends and in direct alignment with the stems of the air-inlet valves 35, the bearings 44 of these shafts being supported in brackets 45 extended from the end casings 8 and 9. Cams 46, 46a are mounted upon these cam-shafts in direct operative alignment with the stems of the valves 35, at each end of the assembly, the arrangement and positioning of these cams being such that as the cam-shafts rotate, the cams at one end of the assembly within each engine unit will simultaneously impinge the heads of the valve stems and open these air-inlet valves for admitting air under pressure into these cylinder ends, while the valves at the opposite end of the assembly within each engine unit remain closed, as required for the compression strokes of the pistons within the cylinders thereof, this action being alternate as between the forward and rear ends of each engine unit, and with equal timing.

A drive or thrust arm 58 is provided for each of the engine units A, B, C, and these arms are extended medially from the forward margins of the cross-yokes 34, in the vertical planes of the piston rods 28 of the several units. These drive arms are preferably formed integral with the said cross-yokes and are formed at their forward ends with the integral connecting rod yokes 50a, the forks of these yokes being transversely bored through to receive the wrist or gudgeon pins 51, upon which these forks are shrunk for securely locking the pins in place. The ends of these pins are extended outwardly of the forks of the yokes, and pairs of roller-rings of conventional structure, designated as rings 52, 52a, are seated upon the extended ends of the wrist pins, there being a pair of these roller-rings at each side of each of the yokes. The inner rings of these roller-ring assemblies or carriers are shrunk upon the ends of the wrist pins and thus firmly seated, while the outer and larger rings 53, 53a, are positioned over the inner rings and rotate thereupon, being supported upon the small rollers 54, 54a. The inner ends of the several connecting rods 55 are oscillatably mounted upon the wrist pins 51 over bushings 51a by seating their half-socketed ends over the wrist pins and then bolting the complementally socketed caps 55a upon their inner extremities within the yokes, as indicated at 56, in conventional manner. The forward ends of the connecting rods 55 are similarly journaled upon the crank-pins of the cranks 39a, 39b, 39c, in the conventional manner indicated at 55b.

An elongated two-part guide-way or race-way casing, formed of the casings 57, 57a, and which are locked together by the set-screws 58, is anchored transversely through between the forward three sets or pairs of cylinders of the engine units A, B, C, the width of this casing being somewhat greater than the length of stroke of the piston rod cross-yokes 34. The casings 57, 57a are chambered out upon their inner adjacent sides to form between them the open race-ways 60a, 60b, 60c, for the three engine units

A, B, C, respectively. These race-ways are formed rectangularly on cross-sections lying in planes cutting the piston rods perpendicularly, and thus they are adapted for freely receiving the three drive arms 56 of the connecting rod yokes of the drive arms as supported upon the roller-ring carriers described. The race-ways are provided at each side with pairs of guide-ways or track-ways 61—61a, and 62—62a, which extend along the upper and lower sides of the race-ways in parallelism with the lines of reciprocation of the yokes 31. The surfaces of these track-ways at top and bottom sides of the race-ways are slightly offset from each other in parallel horizontal planes slightly spaced apart, with the vertical spacings between the upper and lower and vertically aligned track-ways exactly equal.

The vertical spacing between the upper and lower track-ways is accurately gauged so as to nicely receive between them the described roller-ring assemblies or yoke carriers, in such manner that at each side of each race-way, one of the adjacent roller-rings will have traction only on one of the tracks at that side, while its companion roller-ring has traction only on the track extended along the opposite side of the race-way and lying adjacent to the track upon which the other roller-ring has traction. This arrangement is shown in Figure 9, where the inner roller-ring 53 is shown as having traction only on the upper track-ways 61, while the outer roller-ring 53a is shown as having traction only on the lower track-ways 62a. The arrangement is further shown in Figure 5. Thus on the reciprocation of the yokes 50a, one set of the roller-rings will rotate clock-wise while the other set rotates anti-clockwise. By this arrangement it is apparent that the angular thrusts of the connecting rods at either side of the crank-shaft will be received and carried by a set of the roller-rings, in comparatively frictionless manner.

A relatively wide, master spur-gear 64 is keyed upon the extended end of the crank-shaft at the left-hand side of the assembled and encased three-unit engine as described, and spur-gears 65, 66, of equal diameter with each other and with the master gear 64, are keyed upon the opposite ends of the frontal cam-shaft 42, 43, and placed in mesh with the master gear 64 at the upper and lower sides thereof. Similar spur gears 67, 68, of equal diameter with the gears 65, 66, are keyed upon the ends of the cam-shafts 42, 43, at the rear end of the assembly. A train of intermediate intermeshing gears 69, 70, 71, 72, 73, operatively connects the master gear 64 with the rear cam-shaft gears 67, 68. For this purpose the forward gear 69 is of equal diameter with the several cam-shaft gears 65, 66, 67, 68, so that with the gear 69 in mesh with the master gear 64 as shown, and the rear gear 73 in mesh with both of the cam-shaft gears 67, 68, and the intermediate gears 70, 71, 72 in mesh with each other and with the gears 69 and 73, it is obvious that all of the cam-shafts will rotate equally at the engine speed of the crank-shaft. The individual gears of the intermediate gear train are journaled upon studs 74 anchored on a plate 75 mounted on the side of the engine casings or constituting a part of such casings.

As previously stated, the cams 46, 46a of the three engine units are so positioned and keyed upon the cam-shafts, that they all stand turned in the same direction, as indicated in Figure 4. No special forms of air compressors or blowers

or fuel injectors are here shown, and any conventional forms of such devices may be employed. Similarly to the air-inlet valves the fuel injectors may be operated by cams (not shown) mounted on the described cam-shafts, in conventional manner.

The frontal casings 10 and 11 are formed at their lower sides for providing the oil sump 22. As heretofore indicated, the engine casings 6 and 10 and the contained cylinder receptacles mounted therein as described, are separated as to the frontal and rear ends of the assembly on a transverse vertical plane as indicated by the line x in the drawings. This arrangement facilitates or makes possible the proper assembling of the pistons and piston-rod and cross-yoke units, by the stated method of separating the casings 6 and 7 for such purpose, inserting the said units and then bolting the casings together in manner pointed out. Any conventional means may be employed for circulating the cooling liquid employed through the channel-ways 18. Likewise any conventional starting apparatus may be used.

In operation compressed air and oil under pressure, or other combustible in pulverized form are employed. Both cylinders of each engine unit fire simultaneously and build up compression in the two opposite cylinders of that unit, and the units in turn thus operate in succession or rotation due to the fact that their cranks are spaced one hundred and twenty degrees apart around the crank-shaft. The compression ratio will be about fourteen to one. Combustion pressure on one end of each unit works against compression on the opposite end, thus providing easy and smooth running action. At the proper and predetermined angular position of each of the three cranks of the three engine units A, B, C, in succession, at either side of the crank-shaft, a cam on a cam-shaft operates in conventional manner the plunger of a fuel injector, and oil under predetermined pressure is injected through the nozzle ports of the injector into the combustion chambers just as the pistons have compressed air thereinto to the required degree. The heat of compression then explodes this combustible mixture, forcing the pistons at that end over into the opposite end of the engine unit, and in turn compressing the air charges as drawn thereinto through the air-ports, and which air charges are then oil-charged and exploded in turn, in timed succession as to each engine unit. Thus in each engine unit two power strokes are delivered to the crank-shaft on each complete revolution thereof, or for the three engine units a power stroke is imparted at every sixty angular degrees of crank-shaft rotation. Simultaneously and as the several pistons move inwardly, they uncover their exhaust ports and the spent gasses of combustion pass out therethrough, the described tongues of the pistons preventing the back-flow of gasses into the cylinders. Simultaneously with the exhaust phases and in succession as between the three units, the cams on the cam-shafts operate the air-inlet valves and admit compressed air into the cylinders which have just fired, and which expanding downward effectually scavenges the spent gasses of combustion through the exhaust ports, just prior to the reverse reciprocations of the pistons. As a matter of course the most desirable metals or metal alloys would be employed in the construction of these engines, according to the purposes and functions designed to be served.

While I have here shown and described certain embodiments of the invention, and specific structural features thereof, these structural features and details may be changed or altered, within the scope of the claims.

I claim:

1. In an internal combustion engine of the two cycle Diesel type, a pair of elongate cylinders closed at their ends and mounted together side by side in parallel and spaced relation, the cylinders being slotted medially and longitudinally along their inner adjacent sides in their common axial plane, a pair of pistons reciprocally mounted in the ends of each cylinder in exact transverse alignment, a piston rod extended medially and axially within each cylinder and rigidly connected at its ends with the said pistons, and a yoke spanning the space between the cylinders, extended transversely and slidably through the said cylinder slots at each side and rigidly joined at its ends within the cylinders medially to the piston rods, the yoke being less in width than the length of the cylinder slots for permitting reciprocation of the pistons within the cylinders, the said yoke being formed with open and angularly divergent branches at its ends and thereat integrally connected or welded to the piston rods within the cylinders, whereby the piston rods and connecting yoke form an essentially integral structure and best adapted for strength and the radiation of heat for lessening radial expansion.

2. In an assembly according to claim 1, the said cylinders being formed and equipped with air intake ports, exhaust ports, fuel injector ports and devices, valves and timing devices, for operating the unit in accordance with conventional Diesel engine practice.

3. In an assembly according to claim 1, a crank shaft journaled medially and transversely at the forward end of the cylinders, perpendicularly to the plane of the axes of the cylinders, and a connecting rod disposed between the forward ends of the cylinders and operatively connected at its ends to the piston rod yoke and to the crank of the crank-shaft, the said cylinders being formed and equipped with air intake ports, exhaust ports, fuel injector ports, valves and timing devices for operating the dual-cylinder, engine-unit in accordance with conventional two-cycle Diesel engine practice, and whereby a two-fold power impulse may be imparted to the crank-shaft upon each half-turn thereof.

4. In an internal combustion engine of the two-cycle Diesel type, a pair of two-part, elongate cylinders, closed at one end and open at the opposite end, the cylinder parts being rigidly but demountably anchored together in exact longitudinal and axial alignment at their inner, open and abutted ends, the pair of two-part cylinders being rigidly mounted together side by side in exact, spaced and parallel alignment with their axes lying in a common plane, said cylinders being slotted medially and longitudinally along their inner adjacent sides in their common axial plane, pairs of pistons reciprocatingly mounted within the ends of the two-part cylinders and arranged in exact transverse alignment as between the cylinders, axially extended piston rods within the cylinders and rigidly connected at their ends to the said pistons, cross-linkage extended freely through the said cylinder slots and rigidly joined at its ends within the cylinders medially to the piston rods, whereby the piston and rod assembly may reciprocate as a unit, the said cross-linkage being of open work structure for the sake of

strength and heat radiation, and forming with the connected piston rods an essential integral structure.

5. In an engine assembly according to claim 4, the said two-part cylinders and transversely aligned pistons therein being cooperatively formed and equipped, arranged and controlled as to each cylinder part, for alternate and simultaneous two-cycle Diesel engine action in the transversely aligned cylinder ends.

6. In an engine assembly according to claim 4, a crank shaft journaled medially and transversely at the forward end of the cylinder assembly, perpendicularly to the common plane of the axes thereof, a thrust or drive arm medially and rigidly extended from the said cross-linkage of the piston rods, forwardly between the spaced cylinders and arranged to reciprocate longitudinally in the axial plane thereof, a race-way supported between the forward ends of the cylinders and extended longitudinally thereof along their inner adjacent sides, and within which race-way the thrust or drive arm is reciprocably supported, and a connecting rod extended between the forward ends of the cylinders and operatively connected at its ends to the forward end of the thrust or drive arm and to the crank of the crank shaft.

7. In an engine assembly according to claim 4, a crank-shaft journaled medially and transversely at the forward end of the cylinder assembly, perpendicularly to the common plane of the axes thereof, a drive arm medially and rigidly extended from the said cross-linkage of the piston rods, forwardly between the spaced cylinders and arranged to reciprocate longitudinally in the axial plane thereof, a race-way supported between the forward ends of the cylinders and within which the drive arm is reciprocably supported, a connecting rod extended between the forward ends of the cylinders and operatively connected at its ends to the forward end of the drive arm and to the crank of the crank shaft, the said two-part cylinders being formed and equipped at their transversely aligned ends for simultaneous, two-cycle Diesel-type engine action.

8. In a double-action, two-cycle engine assembly, a pair of two-part cylinders demountably assembled in parallel, spaced relation, in exact transverse alignment and in axial alignment as to the parts of each cylinder, the outer ends of the cylinders being closed to provide combustion chambers thereat, the inner ends being open, and there being a cross-yoke clearance space provided at the inner ends of the cylinders for receiving a cross-yoke rigidly connecting a pair of piston-rods extended axially through the inner open ends of the cylinders and supporting at their ends transversely aligned pistons, whereby the pistons, piston rods and cross-yoke may reciprocate as a unit, the said cross-yoke being formed with open and angularly divergent branches at its ends and thereat integrally connected or welded to the piston rods within the cylinders, thereby forming with the rods an integral structure best adapted for strength and heat radiation.

9. In an engine assembly according to claim 8, transversely aligned pistons reciprocably seated in the cylinder ends and rigidly connected by piston rods, a cross-yoke rigidly and transversely connecting the piston rods through the said cross-yoke clearance space, a drive-arm extended forwardly from the cross-yoke between the cylinders, and means at the outer closed ends of the cylinders for simultaneously introducing and exploding in transversely aligned cylinder ends, and

alternately as between the ends of the engine unit, fuel charges within the combustion chambers of transversely aligned pairs of cylinders.

10. In a double-action, two-cycle engine assembly, a pair of two-part cylinders demountably assembled in parallel, spaced relation, in exact transverse alignment and in axial alignment as to the parts of each cylinder, the outer ends of the cylinders being closed to provide combustion chambers thereat, the inner ends being open, and there being a cross-yoke clearance space provided at the inner ends of the cylinders for receiving a cross-yoke, transversely aligned pistons reciprocably seated in the cylinder ends and rigidly connected by piston-rods, a cross-yoke transversely and rigidly connecting the piston rods through the cross-yoke clearance space, a drive-arm extended from the cross-yoke forwardly between the cylinders, and means at the outer ends of the cylinders for introducing and exploding, simultaneously as to the transversely aligned cylinder ends and alternately as to the opposite ends of the engine unit, fuel charges within the combustion chambers of the cylinders, the said cross-yoke being of open work structure flatly extended and including angularly divergent arms integrally connected with the piston rods within the cylinders.

11. In an engine assembly according to claim 10, a connecting rod yoke at the forward end of the drive-arm, a wrist pin passed transversely through the forks of the yoke for receiving the inner end of a connecting rod, a race-way mounted between the forward cylinders of the unit and within which the connecting rod yoke reciprocates, pairs of off-set track-ways comprising part of the race-way and being extended upon opposite sides thereof adjacently the cylinders, the said wrist-pin being outwardly extended at its ends, and pairs of roller-ring bearings mounted on the extended ends of the wrist-pin of the yoke, one pair of the roller-rings having traction on one pair of the track-ways and the other pair of roller-rings having traction on the other pair of track-ways.

12. In an engine assembly according to claim 8, separate casings for supporting the cylinder parts at each end of the assembly, these parts being arranged therein for longitudinal alignment when the casings are assembled end to end, and means for releasably securing the casings together in proper relation.

13. In an engine assembly of the kind described, a pair of engine casings adapted for alignment end to end to complete the engine housing, pairs of cylinder receptacles mounted in each casing in equal parallel spaced relation, in exact transverse alignment as to the receptacles of each casing, and so that when the casings are aligned end to end, the said receptacles will align vertically as to the receptacles of each casing and axially as to the receptacles of the two casings, there being a clearance between the inner ends of the receptacles at their adjacent sides, when the casings are thus aligned, and means for releasably locking the casings together in alignment.

14. In an assembly according to claim 13, cylinder shells seated within the outer ends of the said receptacles, pistons reciprocably mounted within the cylinder shells in exact transverse alignment as to the cylinder shells of each casing, piston rods extended axially through the inner open ends of the longitudinally aligned cylinder shells and rigidly joined at their ends to the pistons therein, a cross-yoke transversely and rigidly connecting the piston rods through the clearance space at the inner ends of the receptacles, a drive arm extended forwardly from the cross-yoke between the cylinders and provided at its forward end with a connecting rod yoke, a race-way mounted between the frontal cylinder receptacles and arranged to receive and support the said cross-yoke in its oscillations, a crank shaft journaled transversely and intermediate of the frontal end of the assembly, a connecting rod operatively connecting the crank of the crank-shaft with the yoke of the drive arm, and means at the outer ends of the cylinder shells for introducing and exploding, simultaneously as to the transversely aligned cylinder ends and alternately as to the opposite ends of the engine unit, fuel charges within the outer ends of the cylinder shells as compressed therein by the pistons, said means being operated and controlled by the crank-shaft.

15. In an engine assembly of the kind described, a two-part housing for the engine parts, comprising a pair of casings for alignment end to end for completing the housing, each casing having pairs of cylinder receptacles arranged therein in equal parallel and spaced alignment and adapted to align axially with each other when the casings are turned together endwise.

16. In a race-way for receiving the drive-arm and connecting rod yoke of a dual-cylinder engine assembly the cylinders being spaced apart in transverse alignment, and the drive arm being extended forwardly between the cylinders from a cross-yoke connecting piston rods within the two cylinders, a race-way housing mounted between the cylinders and chambered out rectangularly in a cross-section cutting the drive-arm perpendicularly, pairs of off-set track-ways extended along opposite sides of the race-way chamber adjacent to the cylinders, a wrist pin seated through the forks of the connecting rod yoke and extended laterally at each side thereof, and pairs of roller-ring bearings mounted on the extended ends of the wrist pin, one set of the roller-rings having traction only on one pair of the track-ways at one side of the race-way chamber and the other set of roller-rings having traction only on the opposite pair of track-ways.

17. In a device according to claim 16, the said race-way housing being of two-part structure and the parts thereof being adjustably locked together by means of set-screws, whereby the tracks of the race-way may be adjusted to the roller-ring assemblies or bearings of the wrist pin carrying the connecting rod yoke.
